UNITED STATES PATENT OFFICE

JOHN P. KOLLA, OF HOLLAND, MICHIGAN, ASSIGNOR TO HOLLAND FURNACE COMPANY,
OF HOLLAND, MICHIGAN

SMOKE BAFFLE FOR FURNACES

Application filed January 9, 1930. Serial No. 419,484.

The object of this invention is to provide an improved construction of smoke baffle plate for retaining smoke and dust in the furnace during the fuel feeding operation.

5 A structure showing an embodiment of my invention is illustrated in the accompanying drawings, in which:

Fig. 1 is the combustion chamber of a hot air furnace with the feed section embodying 10 my invention in perspective, the feed door and other parts of the furnace being omitted.

Fig. 2 is an enlarged detail vertical section on line 2—2 of Fig. 1, showing details of one 15 of the hinge structures for the smoke baffle.

15 The parts will be identified by their numerals of reference which are the same in all the views.

1 is the combustion chamber of a hot air furnace. 2 is the feed section thereof. 3 is an 20 improved baffle plate suspended back of the integral cross rib 21 at the top of said feed section.

25 The baffle plate is perforated at 31 and is held in place by eye-bolt 4, the recurved end of which extends into recesses 22 in the cross rib 21. Cross rib 21 is extended downwardly into strengthening ears 23 at each end.

It will be observed that this baffle plate, if 30 injured, can be very readily removed and a new one substituted. It is very secure when installed and has the utmost freedom of movement. The perforated part turns on the eye-bolt so that it yields readily if struck by the shovel or its contents when charging 35 the furnace. At the same time the plate drops instantly into the baffling position which is especially effective due to the flat surface of the baffle plate coming into contact with the flat side of the strengthening 40 rib above.

I have shown my structure in the precise 45 form which I prefer and which I believe is very advantageous. I desire to claim the same specifically and also broadly as pointed out in the appended claim.

Having thus described my invention, what I claim as new and desire to secure by Letters Patent, is:

50 In combination with a combustion chamber and feed section of a hot air furnace, an

integral supporting rib disposed within the said feed section, transversely across the top thereof and strengthening the same and having its ends extended downwardly to form attaching ears, a flat perforated baffle plate 55 suspended back of said rib and disposed to contact therewith when in depending position, and screw threaded eye-bolts forming hinge members to support said baffle plate inserted through the said rib with their free 60 ends turned upward and engaging depressions in the said rib for retaining the same securely in place, and screw nuts on the outer ends of said bolts.

In witness whereof I have hereunto set my 65 hand.

JOHN P. KOLLA.
